UNITED STATES PATENT OFFICE.

FRANK J. SENG, OF CHICAGO, ILLINOIS, ASSIGNOR TO THE SENG COMPANY,
OF SAME PLACE.

DESIGN FOR A CLUTCH MEMBER.

SPECIFICATION forming part of Design No. 31,083, dated June 27, 1899.

Application filed June 3, 1899. Serial No. 719,315. Term of patent 3½ years.

To all whom it may concern:

Be it known that I, FRANK J. SENG, a citizen of the United States, residing at Chicago, in the county of Cook and State of Illinois, have invented a novel Design for a Clutch Member; and I do hereby declare the following to be a full, clear, and exact description of the invention.

My invention relates to a novel design for a clutch member, the object being to provide a neat and ornamental device of this character.

In the accompanying drawings, illustrating my design, Figure 1 is a perspective view of the clutch member. Fig. 2 is an end elevation of same. Fig. 3 is a top plan view of same.

My design consists of a base or member A, which is flat or plane and practically square and is provided on two edges with two parallel flanges or ears B, extending at angles of about ninety degrees thereto in one direction,

and a similar flange or ear C on a third edge extending in an opposite direction, also at an angle of about ninety degrees thereto. Each of said flanges or ears B and C is of rounded or partially-circular outline, and the corners 25 where said flanges meet said plate are also rounded. Each of said flanges or ears has an opening therethrough which is eccentric to the outline thereof.

My device is very neat and ornamental in 30 appearance.

I claim as my invention—

The design for a clutch member, substantially as shown and described.

In testimony whereof I affix my signature 35 in presence of two witnesses.

FRANK J. SENG.
